UNITED STATES PATENT OFFICE.

FRANK E. BESSLER, OF AKRON, OHIO.

MOVABLE STAIRWAY.

1,219,695.

Specification of Letters Patent. Patented Mar. 20, 1917.

Application filed November 22, 1915. Serial No. 62,834.

To all whom it may concern:

Be it known that I, FRANK E. BESSLER, a citizen of the United States, residing at Akron, in the county of Summit and State 5 of Ohio, have invented a new and useful Movable Stairway, of which the following is a specification.

The device forming the subject matter of this application is a stairway of that general 10 type which is adapted to slide upon a hingedly mounted, ceiling supported panel, the device being of peculiar utility in locations where a fixed stairway is undesirable.

The invention aims to provide novel means 15 for mounting the stairway slidably upon the panel and for controlling the movements of the stairway.

The invention aims to improve the handrail structure.

20 It is within the province of the disclosure to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

In the accompanying drawings:—

35 Figure 1 is a vertical sectional view, most parts of the invention appearing in elevation, and the stairway being lowered with respect to the hinged mounted panel;

40 Fig. 2 is a vertical sectional view disclosing the invention for the most part in elevation, the panel having been swung upwardly, and the stairway having been retracted with respect to the panel;

45 Fig. 3 is a transverse section, the panel having been swung upwardly to a closed position;

50 Fig. 4 is a fragmental longitudinal section showing the latch mechanism whereby the panel is upheld;

55 Fig. 5 is a sectional view wherein the invention is viewed at right angles to the show-

ing of Fig. 1, the stairway having been lowered and the panel having been swung downwardly, as in Fig. 1;

Fig. 6 is a sectional view illustrating in 55 elevation the hinge elements whereby the panel is assembled movably with the panel supporting frame or ceiling;

Fig. 7 is a cross section taken through the 60 spring barrel.

The invention contemplates the use of a frame 1 constituting a part of the ceiling of a room, the numeral 55 denoting the opening through the frame. The numeral 2 indicates a vertically swinging panel. The 65 panel 2 is assembled with the frame 1 by means of hinge members 3 and 4, the hinge members 3 being secured to the frame 1 and the hinge members 4 being secured to the panel 2. The hinge members 4 which are 70 attached to the panel 2 are so constructed that they serve as supports for various parts of the structure. The hinge members 4 each include a standard 5 having a finger 7 and a socket 6. (See Fig. 6). 75

Attached to the panel 2 relatively near to its lower end are standards 8 having inwardly projecting fingers 9.

The invention comprises a sliding stairway denoted by the numeral 10 and including stiles 11 and treads 12. In the stiles 11 of the stairway 10, longitudinal guide grooves 14 are formed, the grooves 14 receiving the fingers 7 of the standards 5 and receiving also the fingers 9 on the standards 8. 80

85 When the stairway 10 is slid upwardly with respect to the panel 2, upward movement of the stairway is limited by means of a stop 16 adapted to abut against the finger 9. Downward movement of the stairway 90 10 is limited by a stop 15 adapted to abut against the finger 7, the stops 15 and 16 being secured to one of the stiles 11 of the stairway 10 and extending across one of the guide grooves 14. Journaled as indicated at 18 in Fig. 6 in the standards 5 is a shaft 17. Journaled for rotation on the shaft 17 and on the standards 8 are wheels 20 which, as shown in Fig. 3, engage the stiles 11 of the stairway 10 and support 100 the latter for sliding movement along the panel 2.

Located between the standards 5 and journaled on the shaft 17 is a main drum 21. Located within the main drum 21 is a coiled spring 22, one end of which is secured to the drum, the other end of which is secured to the shaft 17. One end of a flexible element 23 is secured to the main drum 21 and the other end of the flexible element is secured as indicated at 24 in Fig. 1 to one of the treads 12 of the stairway 10. Secured to the ends of the shaft 17 to rotate therewith are auxiliary drums 25. Flexible elements 26 are secured to the drums 25 and are trained around the drums in an opposite direction to that in which the flexible element 23 is trained around the main drum 21. The flexible elements 26 pass around sheaves 27 journaled for rotation on brackets 28 attached to the frame 1. Secured to each flexible element 28 is a stop 29 adapted to coact with an abutment 30 formed at the upper end of each bracket 28. The depending end of each flexible element 26 is equipped with a traveler 31 embodying a rotatable wheel 32 adapted to slide along a track 33 secured to the panel 2 and extended longitudinally thereof.

Mounted in the panel 2 near to its outer end is a casing 34 in which is slidably mounted a latch 35 adapted to coact with a striking plate 36 on the frame 1. The latch 35 is pivoted to a lever 37 fulcrumed at 38 on the casing 34 and actuated by means of depending flexible element 54. A rod 39 slides in the casing 34 and is pivoted to the lever 37. A compression spring 40 surrounds the rod 39, one end of the spring 40 abutting against the lever 37 and the other end of the spring abutting against the casing 34 to hold the latch 35 in such a position that it will engage automatically with the striking plate 36 when the panel 2 is elevated. The rod 39 is united with a rearwardly and upwardly extended connection 41 attached to one end of a lever 42 fulcrumed at 43 on the panel 2 near to the upper end of the panel. The other end of the lever 42 is operatively connected with an upright lever 44 fulcrumed at 45 (Fig. 6) on one of the standards 5. Preferably, the lever 44 is short, so that it may be actuated readily by the foot of an operator.

The invention comprises a support in the form of a post 46 attached to the socket 6 of the hinge member 4^a. At its upper end, the post 46 is provided with an eye 47. A support 48 is secured to one of the stiles 11 of the stairway 10 and is provided with an eye 49. Mounted to reciprocate in the eyes 47 and 49 is a handrail 50 provided adjacent its ends with stops 51 and 53 and equipped intermediate its ends with a stop 52.

Presupposing that the panel 2 is in the uplifted position of Fig. 2, the operation of the structure is as follows:—

The flexible element 54 is drawn upon, tilting the lever 37, the latter withdrawing the latch 35 from the striking plate 36. The foregoing presupposes that the panel 2 is to be swung downwardly from a point below the panel. If, however, the operator desires to manipulate the latch 35 from a point above the panel, then the actuating train for the latch 35 embodies the foot lever 44, the lever 42, the connection 41, the rod 39 and the lever 37.

When the panel 2 is swung downwardly on the hinge 3—4, the traveler 31 slides to the left (referring to Fig. 1) on the track 33. This operation disposes the traveler 31 in the position of Fig. 1 and increases the power arm of the panel 2, the latter constituting a lever whereby the flexible elements 26 is made to travel the sheaves 27, the stops 29 ultimately coming into contact with the abutments 30 and defining the angle between the panel 2 and the horizontal. When the flexible elements 26 are actuated in the manner hereinbefore described, the auxiliary drums 25 are rotated and with them the shaft 17, this operation serving to put the spring 22 under some tension. The stairway 10 is then slid downwardly with respect to the panel 2, the stiles 11 of the stairway riding on the wheels 20 and the fingers 7 and 9 riding in the grooves 14 of the stairway stiles, the downward sliding movement of the stairway being limited by the coaction between the finger 7 and the stop 15, as shown in Fig. 1. When the stairway 10 is slid downwardly on the panel, the flexible element 23 is drawn upon, the same rotating the main drum 21 on the shaft 17 and putting the spring 22 under further tension. It will now be obvious that the spring 22 is in such a condition that when the stairway 10 is slid upwardly on the panel 2, the spring will materially assist in the upward sliding movement of the stairway, and also assist in raising the panel 110 when the latter is swung upwardly.

In order to dispose the parts from the positions of Fig. 1 to the positions of Fig. 2, the stairway 10 is slid upwardly on the panel 2 and the panel 2 is swung upwardly until the latch 35 engages with the striking plate 36. As the stairway 10 is slid upwardly, the eye 49 on the post 48 first slides along the handrail 50 and then abuts against the stop 52, the handrail 50 then moving upwardly along with the stairway and sliding in the eye 47 of the post 46. Upward sliding movement of the handrail 50 beyond a predetermined point is limited by the engagement between the stop 51 and the eye 49 when the parts are disposed as in Fig. 1, downward sliding movement of the handrail beyond a predetermined point being limited by the coaction between the stop 53 and the eye 47.

The frame 1 is provided with a circum-scribing cleat 100 acting as a stop for the panel 2 when the latter is in closed position.

In my copending applications, Nos. 62,835 and 94,186, movable stairways similar to the one herein disclosed, are described and claimed.

Having thus described the invention, what is claimed is:—

- 10 1. In a device of the class described, a frame; a vertically swinging panel hinged at one end for vertical swinging movement with respect to the frame; coöperating parts comprising a shaft supported for rotation adjacent the hinged end of the panel, and a drum journaled on the shaft; a spring connecting the drum with the shaft; a first flexible element wound in one direction around one of said coöperating parts and connected 15 to the panel; a second flexible element wound in an opposite direction around the other of said coöperating parts and connected to the stairway; frame-carried means receiving the intermediate portion of the first 20 flexible element slidably, and including an abutment; and a stop on the first flexible element and engaging the abutment when the panel is lowered, thereby to limit the downward movement of the panel, to limit 25 the tension imparted to the springs, and to prevent an upward sliding movement of the stairway under the action of the spring.
2. In a device of the class described, a

frame; a panel hingedly mounted with respect to the frame; a stairway slidably supported on the panel; a track extended longitudinally of the panel; a traveler adapted to traverse the track; a flexible supporting element connected with the traveler; frame supported means for receiving the intermediate portion of the supporting element; a supporting element connected with the stairway; and a resilient means with which both supporting elements are operatively connected, the resilient means being operative 40 to aid in raising the panel and to aid in sliding the stairway upwardly.

3. In a device of the class described, a frame; a panel hingedly mounted with respect to the frame; a stairway mounted to 50 slide on the panel; a support carried by the panel; a support carried by the stairway; a handrail slidably mounted in the supports; means for limiting the sliding movement of the handrail; and a projection on the hand 55 rail intermediate the supports and engageable by the lower support to slide the handrail in the upper support when the stairway is slid on the panel.

In testimony that I claim the foregoing 60 as my own, I have hereto affixed my signature in the presence of two witnesses.

FRANK E. BESSLER.
